UNITED STATES PATENT OFFICE.

HENRY D. DESHLER, OF BELVIDERE, NEW JERSEY.

VENDING-MACHINE.

1,107,270.

Specification of Letters Patent.

Patented Aug. 18, 1914.

Application filed May 14, 1913. Serial No. 767,729.

To all whom it may concern:

Be it known that I, HENRY D. DESHLER, a citizen of the United States, residing at Belvidere, in the county of Warren and 5 State of New Jersey, have invented a new and useful Vending-Machine, of which the following is a specification.

The present invention relates to improvements in check control vending machines, 10 one object of the invention being the provision of a compact vending machine in which the articles to be vended and the coin, due to the gravity of both, coöperate to automatically release and deliver an article due 15 to the insertion and gravitation of a coin or of a check.

A further object of the present invention is the provision of resilient means disposed in the path of a coin and released thereby 20 for releasing an article retarding and delivering mechanism, the coin after such operation also assisting due to the action of gravity thereof, and also the gravity of the article vended, to release and deliver such 25 article and set the mechanism for the next succeeding operation.

A still further object of the present invention is the provision of a coin operated registering mechanism for indicating the number 30 of coins placed in the machine.

With the foregoing and other objects in view which will appear as the description proceeds, the invention resides in the combination and arrangement of parts and in the 35 details of construction hereinafter described and claimed, it being understood that changes in the precise embodiment of the invention herein disclosed can be made within the scope of what is claimed without departing from the spirit of the invention.

In the drawings—Figure 1 is a front elevation of the complete machine. Fig. 2 is a section taken on line 2—2 of Fig. 1. Fig. 3 is a rear elevation of the upper portion of the front of the casing showing the coin registering mechanism. Fig. 4 is a front elevation of the article holder and its adjoining mechanism *per se*. Fig. 5 is a section taken on line 5—5 of Fig. 2. Fig. 6 is a section taken on line 6—6 of Fig. 4. Fig. 7 is a vertical sectional view through the lower end of the article holder with the article retarding and delivering members. Figs. 8, 9 and 10 are views illustrating the movements of the coin through the lower end

of the coin chute. Fig. 11 is a detail view illustrating a retarding and delivering mechanism for vending matches. Fig. 12 is an enlarged detail view of one of the star or toothed wheels of the retarding and deliver- 60 ing mechanism.

Referring to the drawings, the numeral 1 designates the vertical support for the machine which has detachably connected thereto the casing 2 by means of the upper lug 3 and the lower projecting end 4. The casing 2 is provided with a coin slot 5 so that when a coin C is introduced therein, the lever 6 pivoted at 7 will be engaged and elevated toward the limiting pin 8, a pin 10 being disposed to 70 limit the lower movement of the lever 6 when returned by the spring 9. The elevation of the lever 6 by a coin raises the resilient member 11 whose pawl 12 engages one tooth 13 of the rotary registering dial 14, a 75 single indicating number of which is observable through the peep-hole 15 of the casing 2. A retarding or arresting pawl 16 is provided to prevent the too far rotation of the dial 14. By this means it will be seen 80 that the dial will record each insertion of a coin through the slot 5 and that the tally thereof will be readily observable to the collector through the peep-hole 15.

The lower portion 17 of the casing con- 85 stitutes the coin receptacle which is provided with the transparent plate 17' so that when the casing 2 is removed for the refilling of the article holder 21, the coins within the holder 17 will be readily discernible, the 90 curved delivery plate 18 forming a cover to prevent the removal of the coins through the opening 19 and also for the proper delivery of the articles A to or through the opening 19. The transparent observation slot 20 is 95 provided in the front of the casing 2 so that a purchaser may readily see the articles and thus be warned when the holder 21 is empty. The two plates 22—22' are carried upon the lower end of the article holder 21 adjacent 100 the outlet end thereof and coact with the curved plates or deflectors 23 and 18 to properly direct the lowermost article A for removal through the aperture 19. Two pairs of elongated apertures 24—24' are formed in 105 the respective plates and have journaled therein the two transverse shafts 25—25'. Each of the respective shafts is provided with two toothed or star wheels 26, the teeth 27 of which are of peculiar construction, as 110

clearly illustrated in Fig. 12, and project through the slots 27 formed in the front and rear walls respectively at the outlet mouth of the holder 21, so that the lowermost article, as shown in Fig. 7 will form a connecting link or cog between such wheels and themselves properly assist in holding the star wheels, as clearly illustrated. A spring 28 is disposed one to each shaft 25—25' to resiliently hold its shaft and compensate for the varying size of the article A and thus prevent any clogging of the delivery mechanism.

A gear 29 is carried by the shaft 25 and meshes with a similar gear 29' carried by the shaft 25', this providing a means whereby both shafts will be rotated consonantly and in the direction of the arrows Fig. 2, to insure the delivery of the article after the release of the shafts 25—25'.

In order to provide a means for locking the shafts 25—25', and permitting the automatic release thereof to deliver one article at a time a wheel 30 is keyed upon one end 25 of the shaft 25 and has a corrugated periphery which provides a plurality of arms 31, one to each tooth 27 of the respective star wheels 26—26'. The corrugated periphery of the wheel 30 is disposed to have a portion thereof projected through the slot 32 at the lower end of the coin chute 33, which is secured to one wall of the article holder 21 inclining slightly to have its coin receiving inlet 34 disposed in registration 30 with the slot 5 of the casing 2.

A locking lever 35 pivoted in the apertured lugs 36 is disposed to have its hooked terminal 37 held resiliently by means of the spring 38 in the path to engage one arm 31 of the wheel 30, as clearly shown in Fig. 8, and thus lock the shafts 25—25' with the parts in the position as shown in Fig. 7. The lower terminal 39 of the spring 38 is disposed to limit the downward movement 40 of the lever 35 and thus retain said lever in proper relation when moved outwardly due to the engagement of the coin C with the roller 40 journaled upon the lever 35 and projected through the slot 41 of the chute 33, and constituting a barrier for the chute but of such slight resistance as to be moved outwardly by the engagement therewith of a gravity fed coin. After the coin has engaged the roller 40 and flexed the lever 35 outwardly against the tension of the spring 38, the terminal 37 is moved from engagement with the arm 31 of the wheel 30 while the preceding arm 31 is engaged by the coin, the parts then being in the position, 50 as shown in dotted lines Fig. 8. The wheel 30 being released, will due to the weight of the article A and the delivery or assisting weight A' and also the weight of the coin upon the arm 31 cause the wheel 30 to be moved in 55 the direction of the arrow or to the position

as shown in Fig. 9, and at which time, the lowermost article will have been delivered to the aperture 19 for removal from the machine. The coin C having moved beyond the wheel 40 will permit the spring 38 to move 70 the lever 35 inwardly and place the locking terminal 37 thereof in the position, as shown in Figs. 8 and 10, at which time the succeeding article A will assume the position, as shown in Fig. 7, for a similar operation. 75 The released coin will pass through the outlet 22 into the coin receptacle 17.

The before mentioned apparatus is particularly designed for vending relatively thin and flat articles or packages, such for 80 instance as chewing-gum, chocolate and the like, but it is evident that the present structure can be readily used with articles, as for instance, shaped similarly to a box of matches, in which the corners are square 85 corners and not rounded, as shown in Fig. 7. It has been found desirable when such is the case, that the shafts 25^a and 25^b, as clearly illustrated in Fig. 11, are provided with wheels 43, the peripheries 44 of which are 90 provided with rubber treads, such treads forming friction means to engage the opposite sides of the box M to retain the same when the machine is inactive or to permit the delivery thereof when the mechanism is 95 released by a coin as before described. It is apparent that the peripheries 44 of the wheels 43, instead of being smooth may be corrugated, or even sharp points or sprocket teeth may be provided, it simply being essential 100 that sufficient gripping surface be provided to prevent the weight of the article vended, when the wheels are locked, from forcing the lowermost article between and through the wheels.

What is claimed is:

1. The combination in a vending machine, of a vending mechanism and coin controlled mechanism for releasing the vending mechanism, the latter mechanism including a coin receiving and actuated wheel, a coin chute leading thereto, a lock for the wheel, and means carried by the lock and disposed in the chute to be engaged by a coin to release the lock and wheel and consequently the vending mechanism, the coin further engaging the wheel and assisting by its weight in the rotation thereof to insure the complete operation of the vending mechanism.

2. The combination in a vending machine, 120 of a vending mechanism and a coin controlled mechanism for releasing the vending mechanism, said latter mechanism including a coin chute, a wheel operably connected to the vending mechanism and having a plurality of coin recesses in the periphery thereof, a lock for the wheel, and means carried by the lock and projecting into the coin chute, whereby when said latter means is engaged by a coin, the lock is released and 130

the coin delivered into one of the recesses of the wheel to assist in the rotation thereof and the operation of the vending mechanism.

3. The combination in a vending machine, of a vending mechanism and a coin controlled mechanism for releasing the vending mechanism, the latter mechanism including a coin chute, a wheel connected to the vending mechanism and having a plurality of 10 coin receptacles in the periphery thereof, said wheel having a portion of its periphery projected within the coin chute, a pivoted locking bar having its free end disposed to engage the wheel to lock the same, and

means carried by said bar and projecting 15 into the coin chute, whereby when engaged by a coin, the locking bar is released and the coin is delivered in one of the receptacles of the wheel to assist in the rotation thereof and the actuation of the vending mechanism. 20

In testimony that I claim the foregoing as my own, I have hereto affixed my signature in the presence of two witnesses.

HENRY D. DESHLER.
